UNITED STATES PATENT OFFICE.

BENJAMIN T. BABBITT, OF NEW YORK, N. Y.

BOILER-FEEDER.

SPECIFICATION forming part of Letters Patent No. 269,993, dated January 2, 1883.

Application filed October 28, 1882. (No model.)

To all whom it may concern:

Be it known that I, BENJAMIN T. BABBITT, a citizen of the United States, residing in the city, county, and State of New York, have invented new and useful Improvements in Boiler-Feeders, of which the following is a specification.

My invention relates to improvements in that kind or description of boiler-feeders which consist of a plug rotating within a shell or casing, and containing separate cavities which are, through proper openings in the shell or casing, alternately filled with water, by gravitation, from a suitably-placed reservoir, and also discharged, by gravitation, into the boiler as the plug rotates, the said plug being arranged centrally on a line with the intended water-level of the boiler, and keeping the water always at the desired level.

The invention consists in a novel system of steam and water passages and cavities provided between the plug and its shell or casing, as hereinafter described and claimed, whereby the pressure of the steam in the boiler acting against one side of the plug is counterbalanced.

The accompanying drawings form part of this specification, and illustrate what I consider the best means of carrying out my invention.

Referring to the drawings, Figure 1 is a sectional view, representing my invention applied in conjunction with a boiler and water-reservoir. Fig. 2 is a central vertical section of my improved boiler-feeder separately on a larger scale. Fig. 3 is a transverse section on the line *x x* of Fig. 2. Fig. 4 is a transverse section on the line *y y* of Fig. 2.

In each of the views similar letters of reference are employed to indicate corresponding parts wherever they occur.

A represents the casing or shell of my improved boiler-feeder, and *B* is the rotating plug thereof. The casing or shell *A* is formed with inlet and outlet openings, and sockets *A'* *A''* on its opposite sides, the socket of the inlet-opening *A'* being tapped to receive the end of a pipe or tube, *C*, connecting with a reservoir, *D*, or other suitable water-supply, and the nozzle of the outlet-opening *A''* being tapped to receive the end of a pipe or tube, *E*, connected with the under side of the boiler *F* at *f*.

G is a steam-pipe, one end, *g*, of which is connected to the upper part of the boiler above the water-level, while its opposite end is tapped into a nozzle, *a*, formed in the side of the outlet-socket *A''* of the shell *A*, for the purpose of admitting steam from the boiler into the outlet *A''* of the shell, and so placing *in equilibrio* the water which is in the pipe *E*, and which is therein cut off from the reservoir by the rotary plug *B*. The rotating plug *B* is constructed with separate cavities *b* *b'*, formed on opposite sides of the plug thereof and divided one from another by a horizontal partition, *b²*. The plug *B* is preferably formed tapering, and adapted to be received in a correspondingly-formed seat, *a'*, in the casing or shell. The taper plug *B* is represented at its end *b³* as held in position by means of a center screw-bearing, *A³*, which is tapped into the end *a''* of the shell *A*, and there retained by a lock or back nut, *A⁴*. The plug *B*, at its opposite end, is formed with a shaft, *B'*, provided with an enlargement, *B²*, adapted to be received within a stuffing-box, *H*.

I is a packing-ring, which, with the cap *J*, screwed onto the tapped end of the casing or shell *A*, serves to form a water and steam tight joint.

The shaft *B'* and its plug *B* may be rotated by means of a crank, *K*, driven by a steam-engine or other suitable power.

l l are steam and water passages, formed within the shell on opposite sides of the outlet-opening *A''*, each of which, by means of an annular passage, *l'*, formed in the shell *A*, communicates with an enlarged cavity, *l²*, formed in the shell *A* on the opposite side of the plug, so that where the discharge is effected the aggregate area of the cavities *l²* should be equal to the sum of the areas of the opening *A''* and passages *l l*.

The operation of the device is as follows: The engine or other operating means being started, the crank *K* will be started, and consequently the plug *B* rotated, and at each revolution one or other of the cavities, *b* or *b'*, will be filled with water gravitating through the pipe or tube *C* from the reservoir *D*. While at the same time the water previously received in the opposite cavity will be discharged by gravitation into the pipe or tube *E*, and thence

delivered into the boiler in the manner common to boiler-feeders of this class, and during this operation the pressure from the boiler acting through the opening A^2 on the lower part 5 of the plug is balanced by the corresponding pressure which reaches the upper part of the plug through the passages l^1 and cavities l^2 in the shell A.

Having thus described my invention, what I 10 claim, and desire to secure by Letters Patent, is—

A device for feeding water to boilers, combining in its structure a shell or casing having

an inlet and an outlet passage, interior balancing-cavities and longitudinal passages for connecting the said cavities through the outlet passage, and an interior rotating plug constructed with water-receiving cavities separated by a partition, said shell or casing having means for connecting it with the steam-space of a boiler, substantially as and for the purpose described.
